US00D933836S

(12) **United States Design Patent** (10) Patent No.: **US D933,836 S**
(45) Date of Patent: **** Oct. 19, 2021**

(54) **TRACER**

(71) Applicant: **TINAVI MEDICAL TECHNOLOGIES CO., LTD.**, Beijing (CN)

(72) Inventors: **Mingming Deng**, Beijing (CN); **Yongqiang Zhao**, Beijing (CN); **Cong Peng**, Beijing (CN)

(73) Assignee: **TINAVI MEDICAL TECHNOLOGIES CO., LTD.**, Beijing (CN)

(**) Term: **15 Years**

(21) Appl. No.: **29/696,110**

(22) Filed: **Jun. 25, 2019**

(30) **Foreign Application Priority Data**

May 15, 2019 (CN) 201930251578.8
(51) LOC (13) Cl. **24-02**

(52) U.S. Cl. ..... USPC **D24/185**

(58) **Field of Classification Search**

USPC D3/203.1, 203.2, 203.3; D6/332, 641, D6/642, 643, 643.1, 644, 645, 646, 647, D6/649, 650, 650.1, 655, 655.1, 655.11, D6/655.12, 655.13, 655.14, 655.15, D6/655.16, 655.17, 655.18, 655.19, 655.2, D6/655.21, 655.22, 655.23, 698, 700, D6/701, 553, 559, 561, 563, 601; D10/40; D13/101, 112, 114, 118, 120, D13/121, 122; D14/300, 301, 302, 307, D14/313, 314; D15/199; D23/200, 202, D23/207, 209, 210, 499; D24/100, 133, D24/144, 158, 159, 160, 162, 163, 164,

CLAIM

The ornamental design for a tracer, as shown and described.

DESCRIPTION

FIG. 1 is a front view of the tracer showing our new design. FIG. 2 is a rear view of the tracer of FIG. 1.

FIG. 3 is a left side view of the tracer of FIG. 1.

FIG. 4 is a right side view of the tracer of FIG. 1.

FIG. 5 is a top view of the tracer of FIG. 1.

FIG. 6 is a bottom view of the tracer of FIG. 1.

FIG. 7 is a bottom, front, and left perspective view of the tracer of FIG. 1; and,

FIG. 8 is a bottom, rear, and right perspective view of the tracer of FIG. 1.

The broken lines illustrate portions of the tracer and form no part of the claimed design.

1 Claim, 8 Drawing Sheets
